Primary Examiner — Philip S Hyder*Assistant Examiner* — Ryan Harvey(74) *Attorney, Agent, or Firm* — Clement Cheng(57) **CLAIM**

The ornamental design for a trampoline, as shown and described.

DESCRIPTION

FIG. 1 is a perspective view.

FIG. 2 is a front view.

FIG. 3 is a rear view.

FIG. 4 is a right view.

FIG. 5 is a left view.

FIG. 6 is a top view; and,

FIG. 7 is a bottom view.

The dotted line disclosure forms no part of the claimed invention.

1 Claim, 5 Drawing Sheets(56)
